UNITED STATES PATENT OFFICE.

JOSEPH M. BARTON, OF DANVERS, MASSACHUSETTS, ASSIGNOR TO UNITED SHOE MACHINERY COMPANY, OF PATERSON, NEW JERSEY, A CORPORATION OF NEW JERSEY.

HEEL-ATTACHING MACHINE.

1,120,667.

Specification of Letters Patent. Patented Dec. 15, 1914.

Application filed April 17, 1908, Serial No. 427,684. Renewed October 16, 1914. Serial No. 867,039.

To all whom it may concern:

Be it known that I, JOSEPH M. BARTON, a citizen of the United States, residing at Danvers, in the county of Essex and Commonwealth of Massachusetts, have invented 5 certain Improvements in Heel-Attaching Machines, of which the following description, in connection with the accompanying drawings, is a specification, like reference characters on the drawings indicating like parts in the several figures.

This invention relates to heel attaching machines.

Where the heels of boots or shoes are 15 face-nailed, they are attached by nails driven through both the top lift and the heel into the heel seat, the ends of the nails being exposed to view in the outer surface of the top lift. Heretofore in this work it has been 20 customary to secure top lifts to heels before the heel attaching operation, this being commonly done in the operation of building the heels.

The primary object of the present invention is to make provision for attaching to a 25 shoe two separate superposed sections of a heel.

To this end an important feature of the invention consists in a holder adapted to retain in position to be attached a plurality of 30 superposed separate sections to form a heel, said holder being so constructed and arranged that it may accommodate sections of different sizes so that shoes of different sizes 35 may be conveniently provided with heels. In order that the sections to form the heel may be securely held in position to be attached, the holder is preferably constructed to exert gripping pressure upon the individual sections, in the plane of each section.

Since the top lift serves as a gage in the heel trimming operation, the position of its rounded end upon the shoe should be determined independently of variations in size 45 of the top lift. The holder herein shown is accordingly so constructed that variations in size of the top lift, such, for example, as may be due to irregular shrinkage, are taken care of, at the breast of the top lift, the 50 curved end of the lift being maintained in a predetermined position. The holder herein shown is also so constructed that irregularities in size of the heel are taken care of at the rear of the heel. To this end the holder 55 is so formed that the breast edges of the heel

and the top lift are maintained in approximately the same vertical plane.

In the particular embodiment of the invention hereinafter described there is provided a stationary rear gage formed and arranged to have engagement with the top lift or outer section of the heel, a movable rear gage arranged for engagement with an inner section of the heel and constructed for rearward yielding movement, and a breast 60 gage arranged for engagement with the breast edges of each of said sections and held yieldingly toward the rear gage. The relative position of the two sections at the breast is determined by the contour of the 65 face of the breast gage, and the position of the curved end of the top lift or outer section with reference to the driver passages of the machine may be varied by adjustment of the stationary rear gage. The movable rear 70 gage, by its yielding movement, compensates for any irregularity in the size of the 75 inner section of the heel.

It will be understood that while the present invention is herein described with reference 80 to attaching heels and top lifts, it may be employed to advantage in other cases where it may be desired to attach to a shoe two separate sections which are to form a heel.

In the drawings, Figure 1 is a view in perspective of a portion of a heel attaching machine equipped with a holder constituting one embodiment of the invention; Fig. 2 is a plan view of the holder and its supporting 90 plate; Fig. 3 is a fragmentary view in vertical section, taken on the line 3-3 of Fig. 2.

Referring to the drawings, the reference numeral 1 indicates the nail block head of a heel attaching machine. The machine to 95 which the invention is shown applied is illustrated and described more fully in Letters Patent of B. F. Mayo No. 884,513, granted April 14, 1908. Upon the head 1 is pivotally mounted at 4 a plate 6. The 100 plate 6 is arranged for swinging movement across the upper surface of the head and carries a holder constructed to grip individually two superposed sections adapted to form a heel. The holder comprises two rear 105 gages and a breast gage between which the sections of the heel are gripped. The rear gages are arranged in a superposed relation. The lower rear gage is provided with a shank 8 which is received in a suitable guide- 110

way upon the plate 6 formed between said plate 6 and a superposed plate 7 secured thereto. The shank 8 of the lower gage is provided at its rear end with a lug 9 entered by an adjusting screw 10 by which this gage may be adjusted longitudinally of the shoe. The shank 8 is provided at its forward end with a fork 12 formed and arranged to have engagement with the rounded end of the lower section of the heel. The upper rear gage, which rests upon the lower gage, has at its forward end a fork 14 formed for engagement with the upper section of the heel, and its shank is provided with an upwardly extending projection 15. A rod 16 extends rearwardly from the projection 15 and enters an orifice in the lug 9 formed upon the end of the shank 8. A coiled spring 18 is arranged about the rod 16 between the projection 15 and the lug 9, and presses the fork 14 forwardly, its forward movement being limited by the contact of the projection 15 with the end of a slot in the plate 7 in which said projection 25 moves, as will appear from Fig. 2. The breast gage illustrated consists of an L-shaped bar 20, one member of which is received in a guideway formed between the plate 6 and the plate 7. The breast gage is 30 pressed toward the rear gage by a spring 22. As will appear from Fig. 3 the inner surface of the gage, which has contact with the breast edges of the sections of the heel, is vertical and is of sufficient height to have 35 contact with both sections of the heel. The lower fork 12 is preferably of a height less than the thickness of the thinnest top lift which may be desired to be attached, so that when the sections of the heel are pressed 40 against the heel seat said fork will be free from engagement with the upper section of the heel.

Prior to use of the mechanism shown and described, the lower fork 12 is adjusted longitudinally of the heel to insure that the rounded end of the top lift will be in correct position longitudinally of the shoe. The position of this fork is varied where change is made in the size of the top lifts 45 being attached. The normal position of the breast gage 20 may also be adjusted in the manner indicated in the patent above referred to.

In the use of the holder shown, a heel blank and a top lift may be placed together in position therein, the breast gage being retracted to permit the insertion of the two superposed sections of a heel. As will appear from Fig. 3, the top lift rests directly 55 upon the upper surface of the nail block, the plate 6 prior to the attaching operation being in the position shown in Fig. 1. The breast gage being released, the sections of the heel are pressed rearwardly into engagement with the rear gages. The pressure

exerted by the breast gage upon the two sections of the heel imparts to them a slight rotatory movement in case their longitudinal axes are out of parallelism with the longitudinal axis of the holder, and thus straightens their breast edges. The lower fork 12 limits rearward movement of the top lift while the upper fork 14 yields to the pressure exerted upon it by the upper section of the heel. To permit this operation, the tension of the spring 22 is sufficient to overcome the resistance of the spring 18. Variations in length of the upper section of the heel are thus taken care of by the yielding movement of the fork 14. It will be understood that the forks 12 and 14 center the rounded ends of the two sections of the heel. The position of each section of the heel in the holder is thus accurately controlled and the two sections are gripped individually and securely held from displacement.

In the attaching operation the attaching nails are driven through the two sections of the heel into the heel seat. As the nail block head 1 descends after the nails are driven, the plate 6 is automatically swung laterally in the manner indicated in the patent above referred to. This brings beneath the heel a spanning portion of the plate 6 which is pressed against the heel in the second upward movement of the head 1 and evens up the surface of the heel, insuring that the ends of the nails will be flush with the surface of the top lift.

While in the holder shown the breast edges of the heel sections are maintained flush with each other, it will be understood that it would be within the present invention to so construct the holder that said edges would not lie in the same vertical plane. The arrangement shown, however, may be advantageous if it is desired that the excess of stock in the upper section of the heel shall lie at the rear of the heel.

As will be obvious, changes may be made in the general arrangement of parts without departing from the present invention. I believe that I am the first to provide a heel attaching machine with a holder for gripping a plurality of superposed sections of a heel adapted to accommodate differing lengths of one or more of the sections and hold them in position to be attached, and I desire to claim the same broadly in whatever specific form it be embodied.

Having described my invention, what I claim as new and desire to secure by Letters Patent of the United States is:—

1. A heel attaching machine, having in combination, means for sustaining a shoe, nail driving means and means for retaining a plurality of superposed separate sections of a heel in predetermined relation to the shoe, said means being constructed to

- exert gripping pressure independently upon each of said sections.
2. A heel attaching machine, having in combination, means for sustaining a shoe, nail driving means and means for holding superposed separate sections of a heel in predetermined relation to the shoe, constructed to grip independently the individual sections by pressure applied longitudinally of the heel.
3. A heel attaching machine, having in combination, means for sustaining a shoe, nail driving means, and means for holding superposed separate sections of a heel in predetermined position to be attached to the shoe constructed to accommodate differing lengths of at least one of said sections and to maintain the breast edges of said sections in a predetermined relation regardless of variations in size.
4. A heel attaching machine, having in combination, means for sustaining a shoe, nail driving means, and means for holding superposed separate sections of a heel in position to be attached to the shoe constructed to accommodate sections of different sizes and to maintain an outer section with its rear end at a predetermined point longitudinally of the shoe.
5. A heel attaching machine, having in combination, means for sustaining a shoe, nail driving means and means for holding superposed separate sections of a heel in position to be attached comprising a stationary rear gage formed and arranged to have engagement with the outer section of the heel, a movable rear gage arranged for engagement with an inner section of the heel and constructed for rearward yielding movement, and a breast gage arranged to have engagement with the breast edges of each of said sections and held yieldingly toward the rear gages.
6. A heel attaching machine, having in combination, means for sustaining a shoe in position to receive a heel, means for driving the attaching nails, means for positioning and retaining an outer section of a two part heel with its rear end at a predetermined point longitudinally of the shoe, and means for gripping a separate inner section independently of the outer section and for retaining it in position relatively to the outer section to be attached simultaneously with the outer section.
7. A heel attaching machine, having in combination, means for sustaining a shoe, nail driving means, means for holding an outer section with its rear end at a predetermined point longitudinally of the shoe, and means for gripping an inner section independently of the outer section and for retaining it with its breast edge in a predetermined relation to the breast edge of the outer section.
8. A heel attaching machine, having in combination, means for sustaining a shoe in position to receive a heel, means for driving the attaching nails and means for holding a plurality of superposed separate sections of a heel in predetermined position to be attached to the shoe, said means being constructed to exert yielding gripping pressure independently upon each of said sections.
9. A heel attaching machine, having, in combination, a shoe support, nail driving means, and means for holding superposed separate sections of a heel in a position to be attached comprising a gage to engage the sections at one end and hold them in a predetermined relation to each other and a double gage to engage the sections at the other end, the parts of which are mounted for relative yielding movement to accommodate varying lengths of the sections.
10. A heel attaching machine, having, in combination, a shoe support, nail driving means, and a combined heel and top lift holder comprising a gage at one end of the work constructed to hold the heel and top lift in a predetermined relative position, a gage at the opposite end of the work to engage the top lift, and a separate yieldingly mounted device to engage the heel and accommodate the portion thereof projecting beyond the top lift.
11. A heel attaching machine, having, in combination, a shoe support, nail driving means, and a combined heel and top lift holder comprising relatively movable end gages at the breast and back of the work both arranged to engage both the heel and top lift concurrently, one of said gages being in two parts having one part yieldingly mounted on the other, and means for holding one of said gages yieldingly toward the other.
12. A heel attaching machine, having in combination, means for sustaining a shoe, nail driving means, and a plurality of separate superposed means for holding superposed separate sections of a heel in predetermined position to be attached to the shoe constructed to adjust themselves relatively to sections of different sizes and to maintain the breast edges of said sections in a predetermined relation regardless of variations in size.
13. A heel attaching machine, having, in combination, a shoe support, nail driving means, and a combined heel and top lift holder having a breast gage, constructed and arranged to engage and aline the breast faces of the heel and top lift, and a back gage comprising a top lift engaging part and a separate relatively movable heel engaging part, the heel engaging part being spring-pressed toward the breast gage.
14. A heel attaching machine having, in combination, a shoe support, nail driving

means, and a combined heel and top lift holder comprising relatively movable end gages at the breast and back of the work, both arranged to engage both the heel and the top lift concurrently, the breast gage being constructed to hold the breast faces of the heel and top lift in alinement and the back gage comprising two separate parts arranged for engagement with the heel and

top lift respectively, one of said parts being 10 mounted to yield relatively to the other.

In testimony whereof I have signed my name to this specification in the presence of two subscribing witnesses.
